IGNITION CONTROL

Stanley M. Udale, Detroit, Mich., assignor to
George M. Holley and Earl Holley

Application January 22, 1945, Serial No. 574,012

7 Claims. (Cl. 123—117)

The object of this invention is to advance the spark at part load to retard the spark at idle and to partially retard the spark at high manifold air pressures.

Figure 1 shows the invention applied to the ignition control of an ordinary supercharged engine used at sea level and up to 10,000 feet.

Figure 2 shows a modification to adapt the device for engines used at altitudes in excess of 10,000 feet.

Figure 3 shows an alternative construction for application to a variable Venturi carburetor.

In Figure 1, air enters at 10 and flows through the venturi 11 to the supercharger 12 past the throttle 13. A port 14 is located adjacent to and on the atmospheric side of the upstream lip of the throttle 13 when closed to the idling position. The opening 15 is located adjacent to and on the engine side of the downstream lip of the throttle 13 when closed to the idling position. The diaphragm 16 is responsive to the pressure differences at the ports 14 and 15 and controls a rod 32.

17 is a connection on the pressure side of the supercharger 12. This pressure is transmitted through a pipe 18 to a chamber 19 where a piston 20 reciprocates. A spring 22 engages with the piston 20 and a spring 21 engages with the diaphragm 16 and thus opposes the spring 22 through the rod 32. An adjustment 23 regulates the springs 21 and 22. A stop 24 limits the idling position of the rod 32, which rod is connected to a circuit breaker 25. When the device is used on an airplane, a connection 17 leads to a chamber 26 (Figure 2), in which is located a barometric element 28, controlling a valve 29 so that the pressure in the pipe 18 is less than the supercharger pressure in 17. The pressure in the pipe 18 escapes through an opening 30 in the piston 20. The stop 31 limits the advance (the maximum possible under cruising conditions) of the ignition system. At idle, the maximum retard is determined by the stop 24. The adjustment 23 takes care of the intermediate spark position during variable load.

In Figure 3, 33 is the air entrance, 34 and 35 are the variable Venturi throttles geared together by the gears 36 and 37. 38 is a fuel passage discharging between two Venturi throttles 34—35. The lever 39 carries an adjustable stop 40, which engages with a valve 41, which is held on its seat by the spring 42. Passage 43 communicates with the chamber 44 to the right of the throttle 34 and communicates through a passage 45 with the throat of the variable venturi. Chamber 46, which contains the spring 42, communicates with the passage 47 and with the chamber 48 above

the diaphragm 49. When the throttles 34—35 assume the idling position, valve 41 rises and permits the passage 43 to communicate with the passage 50, which communicates with the chamber 51 below the diaphragm 49.

Passage 52 communicates with the air entrance 33 and through a restriction 53 with the passage 47. Passage 52 communicates through a restriction 54 with the passage 50. An adjustment 55 regulates the springs 56 and 57. Stop 58 limits the upward travel of the diaphragm 49. An eccentric 59, controlled by a lever 60, limits the downward travel of the diaphragm 49. Fuel enters at 61 and flows into a chamber 62, controlled by two valves 63—64. These valves are controlled by the diaphragms 65—66. The pressure acting on the diaphragms 65—66 is the pressure existing in the air entrance 33, which is admitted through the passage 67. Passage 68 connects the two air chambers 69 and 70 together. Fuel passage 71 is controlled by the movable needle 72, which is moved by the lever 73 and the push rod 74.

Operation of Figures 1 and 2

At idle, the spark is retarded, say to 4° at 550 revolutions per minute. At maximum advance, the advance is to 45° (part throttle cruise), and at wide open throttle, the advance varies, say from 30° at 40" Hg to 35° at 35" Hg. These figures vary with each engine, but the higher the pressure, the lower the spark advance.

At altitude (25,000 feet), the spark retard under the influence of 30" Hg, manifold air pressure will be too great with Figure 1 because the piston 20 will be acted upon by a 15" Hg pressure difference. With the construction shown in Figure 2, the 30" Hg pressure will expand the element 28 and the valve 29 will restrict the flow of compressed air. At sea level, the two devices should be adjusted to give the same advance for the same manifold air pressure. At altitude, it is desirable that the same absolute value of supercharger pressure controls the advance to give the same advance as that found desirable at sea level with the same pressure.

Operation of Figure 3

As the throttle is closed towards the idling position, the adjustable stop 40 engages with the valve 41, which rises and cuts off the connection between chamber 44 and chamber 48 so that the pressure in the chamber 48 becomes atmospheric because of the opening 53. Simultaneously, suction is applied to the chamber 51 through the pipe 50. Therefore, the diaphragm 49 is drawn down

and the spark is retarded. The limit of the retardation due to the idle suction is regulated by the lever 60 and the cam 59, which acts as a stop. As the throttle opened to the position shown in the drawing, the valve 41 is seated by the compression spring 42, and in the position shown, suction from the Venturi passage 45 is transmitted through the passage 43 to the chamber 48, which is located above the diaphragm 49. Diaphragm 49 is thus drawn upwardly and the rod 32 is drawn upward, advancing the spark as far as possible. The limit to the advance of the spark on the part load is determined by the stop 58. When the throttle approaches wide open, the spark assumes an intermediate position, determined by the two springs 56 and 57. This position is determined by the adjustment 55.

What I claim is:

1. In a spark control device for an engine having a circuit breaker, comprising an air entrance leading to the engine, a throttle valve therein, a first port in the air entrance located on the atmospheric side of the throttle when the throttle is closed to the idling position, a second port located on the engine side of the throttle when the throttle is closed to the idling position, a diaphragm responsive to the pressure differences between the two ports, said diaphragm being mechanically connected to said circuit breaker, means whereby when the throttle is opened, the first port is placed on the engine side of the throttle and the second port is placed on the atmospheric side of said throttle, two stops, one for limiting the spark advance when the throttle is opened and the other for limiting the retard when the throttle is closed to the idling position, two yieldable opposed means for moving the diaphragm in each direction and for holding the diaphragm in an intermediate position when the throttle is opened towards the wide open position.

2. A device as set forth in claim 1 in which there is a supercharger connected to the air entrance, a chamber, a passage connecting the supercharger and said chamber, a moving wall in said chamber, said moving wall being mechanically connected to said circuit breaker as to move the circuit breaker towards its retarded position on an increase in supercharger pressure.

3. A device as set forth in claim 1 in which there is a supercharger connected to the air entrance, a chamber, a passage connecting the supercharger to the chamber, a second chamber, a moving wall therein, a passage connecting the two chambers, a valve in said passage, a barometric element in said first chamber connected to said valve, said moving wall being mechanically connected to said circuit breaker so as to move the circuit breaker towards its retarded position on an increase in supercharger pressure and on a decrease in altitude.

4. In a spark control device for an engine having a circuit breaker comprising an air entrance, a throttle valve therein, an air chamber, a diaphragm therein dividing said chamber into two parts, a passage connecting the first part with the suction on the engine side of said throttle, a passage connecting the second part with the pressure existing in the air entrance, valve means interconnected with said throttle for reversing these connections when the throttle is in its idling position, two yieldable means engaging with said diaphragm so as to oppose its movement in either direction and for opposing the engine suction, a connection from the diaphragm to the circuit breaker.

5. A device as set forth in claim 4 in which there are two adjustable stops limiting the travel of the diaphragm in each direction.

6. A device as set forth in claim 4 in which there is an adjustment for adjusting the springs opposing the movement of said diaphragm in either direction in response to said engine suction.

7. In a spark control device for an engine having a variable Venturi throttled carburetor comprising an air chamber, a diaphragm therein dividing said chamber into two parts, a passage connecting the first part to the suction existing in said venturi, valve means operated by said throttle adapted to second part of the chamber to suction existing in the venturi so as to reverse said connection when the throttle is in idling position, two yieldable means for opposing the movements of said diaphragm, a connection from said diaphragm to said spark control device.

STANLEY M. UDALE.
